2 SHEETS—SHEET 2.

UNITED STATES PATENT OFFICE.

STEPHEN STRANSKY, OF PHILADELPHIA, PENNSYLVANIA.

SPRING-BOTTOM FOR BEDS.

1,245,060.

Specification of Letters Patent. Patented Oct. 30, 1917.

Application filed June 15, 1916. Serial No. 103,902.

To all whom it may concern:

Be it known that I, STEPHEN STRANSKY, a citizen of the United States, residing at Philadelphia, in the county of Philadelphia 5 and State of Pennsylvania, have invented certain new and useful Improvements in Spring-Bottoms for Beds, of which the following is a specification.

My invention consists of an improved 10 spring bottom for beds. One of the objects of my invention is to provide a structure of the above described type which will be durable, efficient in its resiliency, and can be adjusted to vary the flexibility and tension of 15 the supporting members thereof.

A further object is to so construct my improved spring bottom that it may be quickly and easily positioned upon or removed from a bed, and the several parts 20 constituting my invention may be quickly and easily detached and assembled.

These objects, and other advantageous ends which will be described hereinafter, I attain in the following manner, reference 25 being had to the accompanying drawings in which

Figure 1 is a fragmentary plan view of my invention.

Fig. 2 is a sectional elevation taken on the 30 line *a—a* of Fig. 1.

Fig. 3 is a transverse sectional elevation taken on the line *b—b* of Fig. 2.

Fig. 4 is an enlarged sectional elevation of one end of a supporting and guiding tube 35 showing certain adjustable members in connection therewith.

Fig. 5 is a fragmentary detached elevation showing certain of the elements of my invention.

40 Figs. 6 and 7 are perspective views of certain of the elements of my invention.

Fig. 8 is a fragmentary end view of one of the two tubular supports which I employ and which shows a slot 25 formed therein.

45 Referring to the drawings, 1 is a frame having transversely extending channel bars 2, and longitudinally extending bars 3.

I have illustrated only one of the longitudinally extending bars 3, but it will be 50 understood that the frame 1 consists of two

of the transverse channel bars 2, and two of the longitudinally extending bars 3 to complete the rectangular frame.

Each of the channel bars 2 is provided with two holes 4, one adjacent each end, and through these holes depend sleeves 5 having cup-shaped upper ends 6 of larger diameter than the holes 4, so that the sleeves will be suspended by the cup-shaped heads 6. Each 55 of the sleeves 5 has a tube 7 slidable therethrough, and each tube has a cotter pin 8 designed to engage the lower end of its sleeve 5.

The upper end of each tube 7 is beaded at 9, and a cup 10 is fitted thereon but is prevented from sliding off the upper end of its tube due to the beaded end 9 forming an abutment.

Spiral springs 11 surround each of the 65 tubes 7, and have their opposite ends respectively engaging the cups 6 and 10, so that any downward movement of the tubes 7 will be cushioned by the springs 11, the cotter pins 8 serving to prevent the springs 11 from moving the sleeves beyond a pre-determined upper position, said position being 70 shown in Fig. 2.

The frame 1 may be secured to the bed proper in any desired manner. Above the 75 frame 1 and the previously described elements, are two tubular supports 12, there being only one illustrated in the accompanying drawings, however, it will be understood that these tubular supports extend parallel to each other, and each is shaped in 80 a manner similar to that shown in Figs. 1 and 2.

Each tubular support 12 has a longitudinally extending slot 13 at one end to provide 85 sliding room for projections 14 on stretching members 15. These stretching members 15 are placed one within each end of the tubular supports 12 having the slots 13 therein.

Each of the stretching members 15 has a 90 threaded opening 16 into which fits the threaded stems 17 of adjusting screws 18.

Casings 19 are secured to each end of the tubular supports 12, and have ends 20 which 95 abut the ends of the tubular supports 12, 100

thus acting as retaining means to keep the stretching members 15 within the tubular supports 12. Each adjusting screw 18 has a head 21 which extends through a hole in its adjacent casing 19, and handles 22 are secured on the heads 21 and have annular flanges 23 which abut the outer surfaces of the ends 20 of the casings 19.

Each of the threaded stems 17 is provided with a threaded collar 24 which is mounted within the casing 19 and acts to prevent accidental longitudinal movement of the threaded stems 17. The opposite end of each of the tubular supports 12 is slotted 15 longitudinally at 25, and this slot extends to said opposite ends of the tubular supports so as to permit the insertion of members 26 which are of the same construction as the stretching members 15.

20 The upper extensions of each of the members 15 and 26 are T-shaped in cross section, the head of the T being indicated in each instance at 27.

25 Transversely extending angle bars 28 and 29 each have slotted openings 30 through which the T-shaped projections of the members 15 and 26 may be inserted.

A flexible fabric 31, which may be made up of a series of flexibly connected links 32 30 having side links 33 hinged at 34, is connected by a series of tension springs 35 to the upwardly projecting legs of the angle bars 28.

35 The ends of the tubular supports which have the slots 25 therein, are provided with casings 36 which are of similar construction to the casings 19 having ends 37 which form abutments for said latter ends of the tubular supports 12.

40 Each of the casings 19 and 36 has a downwardly projecting pin 38. Each of these pins 38 is designed to engage a respective tube 7 as clearly shown in Fig. 2, the lower portions of the casings 19 and 36 engaging 45 the upper beaded ends 9 of said tubes, so that all of the weight supported by the tubular supports 12 is in turn supported by the spring-pressed tubes 7.

45 As a means for securing the bars 3 to the channel bars 2, I provide plates 39, each having an end 40 engaging the lower surface of the channel bars 2, and an up-turned flange 41 which engages the outer faces of the bars 3. The lower edges of the bars 3 55 rest on the upper surfaces of the plates 39 (see Fig. 3), and clamping means including screw bolts 42 and wing nuts 43 tend to bind the plate and the bars 2 and 3 together.

50 Each of the plates 39 is preferably provided with a slot 44 to permit of any lateral adjustment necessary, this slot being of such width as to permit the free movement of the threaded end of the screw bolt 42 there-through, but of smaller width than the di-

ameter of the sleeve portion 45 of the wing 65 nut 43.

It will thus be understood that the springs 11 form a resilient support to accommodate any direct vertical movement required by the tubular supports 12 and their co-acting 70 elements, and the springs 35 yield to permit the desired flexing of the links 32 and side members 23.

More or less tension may be placed upon the links 32 and members 33 by a turning 75 movement of the handles 22, since the movement of the handles 22 causes a relative movement of the threaded stems 17 and thereby effects movement of the stretching members 15.

The members 26 will, in their operative position, engage the inner end of the slot 25, and thereby prevent further movement toward the middle of the tubular supports 12.

Each of the cups 6 on the tubes 7 is provided with ears 47 having holes therein through which screws 48 may be secured to the channel bars 2, so that the tubes are rigidly held to said channel bars.

20 The casings 19 and 36 are each open at their upper ends to permit the projections of the members 15 and 26 to extend therethrough, so that a positive and free sliding movement may be secured by the stretching members 15, which act to move the angle 95 bars 28 in the direction of the slots 13.

The casings 19 and 36 are held securely to the tubular supports 12 by means of set screws 46, so that said supports form stationary guideways and permit the stretching 100 members to slide freely and easily.

It will be further understood that if it is desired to remove the tubular supports and the parts connected thereto from the tubes 7, it is merely necessary to raise the pins 38 105 out of the tubes. Furthermore, the angle bars 28 may be removed bodily with the flexible fabric 31 and springs 35 by turning the handles 22 to permit the rearward movement of the stretching members 15 to such 110 position that the T-shaped heads of said stretching members are opposite the corresponding openings within the bars 28 when the entire super-structure may be raised therefrom.

115 While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, 125 what I claim as new and desire to secure by Letters Patent is:

1. The combination in a bed bottom, of

longitudinally extending tubular supports, said supports having slots therein, transversely extending members movable relatively to each other in the direction of the 5 length of said slots, stretching members having portions positioned within said tubular supports and projections extending through said slots, flexible means connecting said transversely extending members, 10 threaded adjusting members positioned within said tubular supports and engaging a threaded opening in said stretching members, means for holding said threaded adjusting members against longitudinal movement relative to said tubular supports, casings on said tubular supports and having portions engaging the ends thereof, said casings having openings in their end through which said threaded adjusting members extend, depending pins on said casings, and supporting sleeves into which said pins extend, substantially as described.

2. The combination in a bed bottom, of longitudinally extending supporting members designed to be secured to a bed, transversely extending members having T-shaped openings therein and supported by said supporting members, said transversely extending members being movable relatively to 25 each other, flexible means connecting said transverse members, stretching members having T-shaped heads designed to extend through the openings in the transversely extending members whereby said transversely 30 extending members are secured adjacent the first-mentioned supporting members, and means for moving said stretching members whereby their T-shaped heads will first slide within said openings in the transverse 35 members, and afterward actuate them to stretch said flexible connecting means, substantially as described.

3. The combination in a bed bottom, of longitudinally extending tubular supports, said 40 supports having slots therein, transversely extending members having slots therein of varying widths and movable relatively to each other in the direction of the length of said slots, stretching members having portions positioned within said tubular supports and free ended projections extending through said slots in the tubular supports and said transverse members, said free ended projections having enlarged portions 45 capable of passing through the widest portions of the slots in said transverse members but incapable of passing through the narrow portions of said latter slots, flexible means connecting said transversely extending members, and means for moving said stretching members relatively to said supports to stretch said flexible means, substantially as described.

4. The combination in a bed bottom, of a 50 tubular support having a slot extending in from one end, a casing fitting on said support and having a slot for registering with the slot in the support, said casing including an end portion designed to embrace the end of said support and having a hole therein, 55 a member extending transversely to said support, flexible means connected to said transverse member, a threaded stretching member slideable within said support and having a portion extending through the 60 slots of said casing and support into engagement with said transversely extending member, a screw extending through the hole in said casing and into said support, a threaded collar on said screw interposed between the stretching member and the end of said casing, substantially as described.

5. The combination in a bed bottom, of a tubular support having a slot extending in from one end, a casing fitting on said support and having a slot for registering with the slot in the support, said casing including an end portion designed to embrace and cover the end of said support and having a hole therein, a member extending transversely to said support, flexible means connected to said transverse member, a threaded stretching member slideable within said support and having a portion extending through the slots of said casing and support 65 into engagement with said transversely extending member, a screw extending through the hole in said casing and into said support, a threaded collar on said screw interposed between the stretching member and the end 70 of said casing, said collar being designed to abut the inner surface of the end of said casing, a head on said screw outside of said casing, said head having a portion of greater cross section than the width of said hole in 75 the end of the casing whereby said head abuts the outer face of said end of the casing, substantially as described.

6. The combination in a bed bottom, of longitudinally extending tubular supports, 80 said supports having slots therein, transversely extending members movable relatively to each other in the direction of the length of said slots, stretching members having portions positioned within said tubular supports and projections extending through said slots, resilient means connecting said transversely extending members, threaded 85 adjusting members positioned within said tubular supports and engaging a threaded opening in said stretching members, means for holding said threaded adjusting members against longitudinal movement relative to said tubular supports, said transversely extending members having T-shaped 90 slots therein, said stretching members having T-shaped heads movable through said T-shaped slots, means for turning said 95

threaded adjusting members to move said stretching members longitudinally to bring said T-shaped heads into engagement with said transversely extending members where-
5 by the latter are movable relative to each other to vary the tension of said flexible means, substantially as described.

In testimony whereof I have signed my name to this specification in the presence of two subscribing witnesses.

STEPHEN STRANSKY.
